UNITED STATES PATENT OFFICE.

OLIVER C. GREEN, OF DUBLIN, INDIANA.

CLOTHES-RACK.

Specification of Letters Patent No. 25,820, dated October 18, 1859.

To all whom it may concern:

Be it known that I, OLIVER C. GREEN, of Dublin, Wayne county, Indiana, have invented certain new and useful Improvements 5 in Clothes Racks or Frames, and do hereby declare the following to be a full, clear, and exact description thereof, reference being had to the accompanying drawings, making part of this specification.

10 My invention consists in a device by which the cords of a folding clothes frame may be tightened at pleasure without previous loosening and without requiring to be either shortened or changed in position, the same 15 device also allowing the feet of the frame to be adjusted to suit an uneven floor.

My invention further consists in constructing the frame of a rhomboidal in preference to the now used rectangular shape, the said 20 rhomboidal shape offering greater facilities for removal through doorways, &c., with the same surface presented on which to hang clothes.

In the accompanying drawings, Figure 1 25 is a perspective view of the frame or rack. Fig. 2 is a view of the frame when folded. Fig. 3 is a plan.

A is the center post of frame on which, near the top, a series of notches are formed 30 on each of its sides. Pivoted, one on each

side of the post A near the bottom, are the four arms B, B, and C, C. Hinged or pivoted to the sides of the arms B, C, are the pawls or braces D, and E. The arms and pawls B, and D, are longer than C, and E, 35 in order that when stretched into position the cords F, which are fastened on the sides of the arms, may present a rhomboidal form.

The ends of the pawls fit the notches *a* of 40 the center post, and when it is necessary that the cords should be tightened the pawls have only to be moved down the post in lower notches and the object is accomplished. When the feet of the frame do not bear 45 equally on the ground, a slight adjustment of one or more pawls effects an equal bearing.

I claim as new and of my invention herein and desire to secure by Letters Patent:— 50

The combination and arrangement of the center post A *a*, arms B, C, and braces D, E, operating in the manner and for the purposes set forth.

In testimony of which invention, I here- 55 unto set my hand.

OLIVER C. GREEN.
